COMBINED TAPE DISPENSING CABINET AND DRAWERS THEREFOR

Milton Rosenblum, 8-01 Plymouth Drive,
Fair Lawn, N.J. 07509

Filed Oct. 26, 1970, Ser. No. 25,657

Term of patent 14 years

Int. Cl. D3—02
U.S. Cl. D52—2

FIG. 1 is a perspective view of a tape dispensing cabinet showing my new design;

FIG. 2 is a perspective view of FIG. 1 wherein the face plate is shown in its removed condition;

FIG. 3 is a rear and opposite side perspective view of FIG. 1; and

FIG. 4 is an enlarged and separated view of one of the tape drawers therefor.

I claim:

The ornamental design for a combined tape dispensing cabinet and drawers therefor, substantially as shown and described.
